CLAIM

The ornamental design for a coffee press and beverage container as shown and described.

DESCRIPTION

FIG. 1 is a top perspective view of a coffee press and beverage container showing our new design, wherein an outer cylinder of the coffee press and body of the beverage container are shaded to indicate translucency; FIG. 2 is a side view thereof;

FIG. 3 is another side view thereof;

FIG. 4 is another side view thereof;

FIG. 5 is another side view thereof;

FIG. 6 is a top view thereof; and,

FIG. 7 is a bottom view thereof.

In the drawings, the dash/dash broken lines depict portions of the coffee press and beverage container and form no part of the claimed design. The dot/dash broken lines define the bounds of the claimed design and form no part thereof.
